UNITED STATES PATENT OFFICE

WENDELL L. CARLSON, OF HADDONFIELD, NEW JERSEY, ASSIGNOR TO GENERAL ELECTRIC COMPANY, A CORPORATION OF NEW YORK

OSCILLATOR COUPLING CIRCUIT FOR HETERODYNE RECEIVERS

Application filed October 7, 1930. Serial No. 487,047.

The present invention relates to heterodyne radio receiving apparatus, and more particularly it relates to an oscillator coupling circuit for apparatus of that character.

5 In heterodyne receiving apparatus it is customary to provide an oscillation generator or oscillator adapted to deliver a relatively high oscillation voltage and to derive therefrom a relatively low voltage for beating with received signals to produce the intermediate frequency.

10 The use of a high oscillation voltage has the disadvantage that precautions must be taken to prevent radiation from the oscillator which would cause interference to associated or nearby apparatus, and that the coupling does not provide for uniform sensitivity over a given range of frequencies, such as the broadcast band for example.

20 Various expedients have been provided for preventing radiation from oscillators in connection with heterodyne receiving apparatus, including the provision of means for loading the tuned circuit of the oscillator.

25 The loading means is effective in reducing radiation but must be arranged to provide no appreciable initial load, in order that oscillations may be permitted to start. The control of oscillation voltage by loading has the 30 disadvantage that the load tends to change the operating characteristic and resistance of the circuit to which it is applied. However the loading principle may effectively be carried out in connection with an oscillator for

35 a heterodyne radio receiving apparatus, and it is the object of the present invention to provide an improved oscillator coupling circuit for apparatus of that type, in which are eliminated the above-named and other disadvantages common to circuits heretofore used and which provides means for effectively coupling the oscillator to the heterodyne detector.

40 The invention will better be understood from the following description when taken in connection with the accompanying drawing and its scope will be pointed out in the appended claim.

45 In the drawing the figure is a schematic

wiring diagram of an oscillator coupling circuit embodying the invention.

Referring to the drawing, 5 is a heterodyne detector of the hot-cathode electric-discharge type having a cathode 6, an anode 7 and two grid electrodes 8 and 9. This may be a screen grid tube in which the control electrode or grid 8 is interposed between the cathode 6 and the second control electrode or screen grid 9.

50 The detector is connected in the signal channel of the receiving apparatus through the medium of a signal input circuit 10, and an output circuit 11 which serves to conduct from the detector the combined signal and oscillation frequency, or the intermediate frequency. In the present example the input circuit is connected with grid electrode 9 through a suitable tuned coupling transformer 12, and the anode 7 is connected with the output circuit 11 through a second tuned transformer 13 representing any suitable coupling device between the detector and the output circuit. Bias, cathode and anode voltages are supplied to the detector from any suitable source such as batteries 14, 15 and 16 respectively.

55 The grid electrode 8 is directly connected with a tuned circuit 17 of an oscillation generator or oscillator, which in the present example employs as an oscillation device an electric discharge device 18 having a control grid 19 connected with the tuned circuit 17 and provided with a suitable grid condenser 20 and grid resistor 21. The oscillator may 60 be of any suitable type having an oscillatory circuit such as circuit 17. In the present example circuit 17 includes an inductance 22 tuned by a condenser 23. The oscillator device 18 receives its anode potential from the 65 source 16 and its cathode potential from a source 24.

70 The grid electrode 8 of the detector device 5 is connected through the oscillator tuned circuit 17 in such a manner, as indicated in the drawing, that it receives its potential from the source 14. Both of the grid electrodes of the detector device 5 are therefore at the same negative potential, in the present example.

75 It will be seen that the detector device in 80

the above described circuit is connected in the signal channel, as a space charge device, since the signal is arranged to be applied to the outer grid. In the ordinary operation of a four-electrode electric-discharge device or a space charge device, the inner grid adjacent the cathode is operated at a constant positive potential. In the present example it is operated at a positive potential during each positive half cycle of the voltage wave supplied by the oscillation generator, that is, during the half cycle when the oscillator grid is positive.

During the positive half cycle, through the direct coupling between the space charge grid 8 and the tuned circuit of the oscillation generator, the grid 8 also becomes positive and loads the oscillation generator circuit, thereby preventing the amplitude of the oscillations from becoming excessively high and causing radiation.

At the same time, the variation of the voltage set up by the oscillator on the space charge grid causes the output impedance of the detector to vary correspondingly and applies the oscillation frequency to the output circuit along with the signal frequency in the output circuit provided by the application of the signal frequency to the control grid 9 from the input circuit 10. A combined or intermediate frequency is therefore applied to the output circuit 11.

The device 5 therefore operates as a combined detector and loading device, directly connected with the heterodyne oscillator tuned circuit, and has the advantage that because of the direct connection and because of the space charge operation of the detector a low generator oscillation voltage is sufficient to apply the oscillation frequency to the signal channel, thereby reducing the interference or radiation from the oscillator and permitting a more uniform signal response. Furthermore, the loading of the oscillator by the detector tube is such that the oscillation strength is reduced without preventing the oscillator from starting or maintaining oscillations.

Stated in another way the above-described arrangement includes an oscillation generator loaded and prevented from reaching oscillation voltages of excessively high amplitude by a loading device including the space charge grid of a four element electric discharge device which serves as a detector and is thus directly coupled with the oscillation generator, resulting in a more uniform response, lower oscillation voltages and lower interference radiation.

What I claim as new and desire to secure by Letters Patent of the United States, is,—

In a radio receiving apparatus of the heterodyne type, the combination of an oscillation generator including a tuned circuit and an electric discharge device having a grid

electrode, said tuned circuit being connected with said grid electrode and arranged to have oscillations excited therein by said discharge device, and an electric discharge detector having an anode, a control grid, a space charge grid, and a cathode, said space charge grid being directly connected with said tuned oscillator circuit whereby said space charge grid provides a load for said oscillation generator, a source of unidirectional potential connected between said space charge grid and said cathode to impress a negative potential on said space charge grid with respect to said cathode thereby to prevent initial loading of said oscillation generator, a signal input circuit connected with said control grid, and a signal output circuit connected with said anode.

In witness whereof, I have hereunto set my hand this second day of October, 1930.

WENDELL L. CARLSON.
